UNITED STATES PATENT OFFICE

2,666,515

PLURAL KEYBOARD TYPEWRITING
MACHINE

Claude Wellington Brumhill, Leicester, and
Arthur Pateman, Rothley, England, assignors
to The Imperial Typewriter Company Limited,
Leicester, England

Application December 19, 1950, Serial No. 201,638

Claims priority, application Great Britain
December 20, 1949

8 Claims. (Cl. 197—5)

1

This invention concerns typewriting and like machines and its chief object is the provision of a machine which has more than one keyboard, which keyboards may be employed alternatively at the will of the operator. Thus for example there may be one keyboard employing ordinary characters and another keyboard employing different characters such for example as mathematical or chemical symbols or the characters of a foreign alphabet.

With this object in view the invention provides a typewriter or like machine having a plurality of keyboard units each of which is of the type comprising a keyboard with type heads operable, by manipulation of keys, to strike at a typing station, and thereby to co-operate with a reciprocatable and rotatable platen, the typing stations of the several units being spaced apart, and a common carriage unit bodily displaceable into operative association with any selected unit, which carriage unit comprises a runway, a slide reciprocatably mounted thereon, and a platen rotatably carried by the slide with its axis disposed in the direction of reciprocation. It will readily be appreciated that by shifting the carriage unit into association with any selected one of the keyboard units the machine is brought into condition to use the keyboard of that unit and this change-over is effected without in any way restricting the travel of the platen or restricting that portion of the length of the platen that may usefully be employed.

The keyboard units (which may be two or more in number) are preferably located side by side in which case the carriage unit is mounted in the machine for bodily displacement from one unit to another in the axial direction of the platen.

In this construction the danger may occur that during displacement of the carriage unit and particularly when the carriage unit is brought to rest in its new position, the platen may shift endwise in relation to this unit. In order to avoid this possibility it is preferred to provide the machine with means for locking the slide against movement along the runway during displacement of the carriage unit.

According to an important subsidiary feature of the invention the carriage unit incorporates means for traversing the platen in typing, and a control connection for said means, and each keyboard unit comprises an operating connection operable by actuation of the keys to operate the control connection when the carriage unit is associated with that keyboard unit.

2

According to a further important feature of the invention the runway, slide, and platen are comprised in a carriage which is bodily removable from the machine. This permits the substitution of carriages bearing platens of differing lengths. For this purpose the carriage unit preferably comprises a base and means for detachably mounting the runway of the carriage thereon. In such an arrangement the machine may

10 incorporate the slide locking mechanism forming the subject of British Letters Patent 548,059 and/or a draw-band anchorage arrangement forming the subject matter of British Letters Patent 547,895.

15 Ribbon feeding mechanism may be provided in association with each keyboard unit, but preferably the ribbon feeding mechanism is incorporated in the carriage unit. For example it may be arranged on the base before mentioned.

20 The foregoing and other features of the invention are incorporated in the plural keyboard machines which will now be described as examples, with reference to the accompanying drawings in which

25 Figure 1 is a perspective view of a dual keyboard machine;

Figure 2 is a plan view thereof, being to some extent diagrammatic and omitting the carriage for the sake of clarity.

30 Figure 3 is a cross section through the machine;

Figure 4 is a fragmentary perspective view illustrating the carriage locking device;

Figure 5 is a scrap section showing mechanism for locking the carriage down and the handle for lifting and sliding the carriage;

Figure 6 is an end view of the carriage slide and runway clamped to the top plate, while

Figure 7 is a longitudinal section through the top plate and associated parts showing the clamping mechanism;

Figure 8 is a plan view of the top plate, illustrating the ribbon feeding mechanism;

Figure 9 is a perspective view of part of that mechanism;

Figure 10 is a perspective view of a triple keyboard machine.

The machine shown in Figs. 1 and 2 incorporates two standard keyboard units 1a, 1b arranged side by side; an even greater number of units may be employed and by way of example Fig. 10 shows a machine having three units 1a, 1b, 1c. Each unit and frame is mechanically identical and therefore it will, in general, be necessary to describe only those parts which pertain to a representative unit or frame; where

it is necessary to identify like parts in the various units, or frames, they are given the same reference number with the addition of the reference letter *a*, *b*, or *c* as the case may be. Thus for example in Figs. 1 and 2 the keyboards of the two units *1a*, *1b* are respectively indicated at *5a*, *5b*.

For each keyboard unit there is a frame (such as *2a* and *2b* in Figs. 1 and 2, and *2a*, *2b*, *2c* in Fig. 10) and the frames are connected to one another, conveniently by means of longitudinal bars *3*, *4* extending beneath them.

Each keyboard unit is removable bodily from its frame in a manner already known in connection with "Imperial" typewriters, being normally located in a suitable cavity such as *6a*, *6b*, in the appropriate frame. The locating means is well understood and is clearly shown in Fig. 3 in relation to unit *1a*, and is further illustrated in Fig. 2. Considering unit *1a*, the frame *1a* thereof has, at its sides, studs *8*, *9* and *8'*, *9'* respectively which rest on runners *10*, *10'*; studs *9*, *9'* are latched in position by finger-operable latch mechanisms *11*, *11'*.

Each keyboard unit comprises the usual keyboard such as *5a* or *5b* comprising an appropriate arrangement of keys *12a* or *12b* connected by suitable mechanisms (see *14a*, Fig. 3) to type heads *13a* or *13b* capable of striking at a typing station T. S.*a* or T. S.*b*, centrally disposed in the unit, a letter spacing bar *15a* or *15b*, a back-spacer key *16a* or *16b*, a tabulator key *17a* or *17b*, and a margin release key *18a* or *18b*. Each unit also incorporates a universal bar frame *19a* or *19b* for operating the escapement *20* hereinafter referred to. This bar frame constitutes the operating connection hereinbefore referred to and is itself operable by each of the keys and by the letter spacing bar in known manner. In Fig. 3 the bar frame *19a* for the unit *1a* is shown, illustration of the like parts in unit *1b* being unnecessary as both keyboard units are identical in these respects. When a key is struck and the associated type head *13a* swings up about pivot *91a*, a heel *92a* on the type bar *93a* strikes and moves the associated universal bar frame *19a*.

Extending horizontally along the back of the frames *2a*, *2b* there is a pivot bar *21* and on this bar a carriage unit *22* is pivotally and slidably mounted by a plate like member *23* which is referred to as a top plate because it is arranged to be applied to the top of the frame of any selected one of the keyboard units. By pivotal and slideable movement on the bar *21*, this top plate *23* may be brought on to the top of the frame of the selected keyboard unit, and each of these frames is provided with appropriate locating surfaces for locating the plate in position, both against downward movement and against movement lengthwise of the bar *21*. The surfaces providing location against downward movement are indicated at *24* and *124* in Fig. 5, and those providing location against endwise movement at *125*. These surfaces are disconnected by swinging the top plate *23* up about the bar *21*. Means *30*, Fig. 5, also provides for latching the top plate *23* in position. This means comprises a latch *25a* or *25b* in each frame and a depending tongue *26* on the top plate. As the top plate *23* is lowered into position the tongue *26* engages an incline *27* on the latch and deflects the latter against a spring bias until the nose *28* of the latch comes opposite a hole *29* in the tongue whereupon the nose hooks into the hole and so latches the top plate against inad-

vertent upward movement. In order to release this latching mechanism *30* and to raise the top plate *23* the latter is provided with an appropriate handle *31* which has a limited pivotal movement about a horizontal axis *32* and has the tongue *26* attached to it. Thus initial upward movement of the handle disengages the tongue *26* from the latch *25a* or *25b* and further upward movement of the handle raises the top plate *23*.

Upward movement of the top plate may be assisted by at least one spring-loaded plunger *33*, *33'* on the frames which plunger bears against the under side of the top plate.

For guiding the top plate *23* in its movement along the bar *21* and for ensuring that this movement takes place in such an attitude that the top plate and its associated parts will not foul any of the mechanism associated with the keyboard units, there is an arm which protrudes upwards at each region between successive frames and at its top carries a roller. Thus in the dual machine shown in Fig. 1 there is an arm *34*, with its roller *35*, between frames *2a*, *2b*. On the front edge of the top plate *23* there is a horizontal guide channel *36* and when the top plate is raised one end of this guide channel *36* is brought opposite the roller *35* so that when the top plate is moved along its pivot bar *21* by the handle *31* the roller enters the guide channel. Thereby the top plate *23* is positioned during its displacement until the roller *35* emerges from the other end of the guide channel *36* when the top plate has reached a position above the next keyboard unit.

The top plate *23* constitutes the base of carriage unit *22* and it will therefore be appreciated that by shifting the top plate along its pivot bar the carriage unit may be brought into operative association with any selected keyboard unit. In the triple keyboard machine shown in Fig. 10 there is one arm *34a* between frames *2a*, *2b* and an arm *34b* between frames *2b*, *2c*, so that top plate *23* can only be raised or lowered when it is properly located above one of the three units *1a*, *1b* or *1c*.

The carriage unit *22* comprises a horizontal runway *37* on the base *23*, a slide *38* reciprocatably mounted on the runway, and a platen rotatably carried by the slide with its axis horizontal. The runway *37*, slide *38* and platen *39* may be constructed as a unit or "carriage" *40* which is removable in known manner from the base *23* so that carriages with platens of differing lengths may be substituted one for another. For this purpose the carriage unit *22* may incorporate the subject matter of British Patents 547,895 and 548,509. As best shown in Figs. 6 and 7, the carriage *40* is removably located by studs or dowels *41*, *41'*, fixed in the base *23*, which fit in holes *42*, *42'*, in the runway *37*. These studs have heads *43*, *43'* respectively which protrude through holes *44*, *44'* in wedges *45*, *45'*, the latter being biased by springs *46*, *46'*, to engage under the heads and thereby to prevent the carriage *40* being lifted off. When it is desired to lift the carriage off the studs *41*, *41'*, the wedges are moved inwards, against the spring action, by pressure exerted on press buttons *47*, *47'* until said wedges disengage from the heads *43*, *43'*.

The carriage unit *22* incorporates all mechanisms commonly found in association with the carriage of a typewriter. Among these mechanisms there is the usual carriage traversing mechanism. This mechanism comprises a spring loaded spool *48* on the underside of the top plate,

a draw band 49 wound thereon and having its end releasably connected to the slide 38 at 50 (which items 48, 49 and 50 are shown in chain dotted lines in Fig. 3), and an escapement 20 for permitting such limited rotation of the spool 48 upon actuation of any key of the operative keyboard unit as will result in the platen 39 being traversed by one letter space. This escapement 20 incorporates a control connection 51 which, by displacement of the carriage unit 22, is brought into operative association with an element 52a or 52b of the universal frame 19a or 19b of the selected keyboard unit, so that when any key of the latter is struck the platen 39 is moved one letter space to the left.

The carriage unit 22 further incorporates ribbon feeding mechanism for feeding a typewriter ribbon 53 at the front of the carriage 40 past a location S which is centrally disposed in the length of the carriage unit 22 and which, when the carriage unit is associated with any selected keyboard unit, coincides with the typing station T. S.a or T. S.b of that keyboard unit.

The ribbon feeding mechanism is of itself of known kind resulting in the ribbon 53 being fed by one letter space each time one of the keys is struck. It conveniently comprises two housings 70, 71 on the top plate one for a supply spool and another for a take-up spool, together with mechanism for racking the take-up spool around step by step, one step each time a key is struck. Matters may be so arranged that the take-up motion may be applied to either of the spools so that after the used ribbon has been wound up on one spool the latter ceases to become the take-up spool and the take-up motions are applied to the spool from which the ribbon has just been wound so that the ribbon is wound back again. The ribbon-feeding mechanism is mounted on the carriage unit and is operable in each of the alternative positions of that unit by a driver 82a or 82b, in the associated keyboard unit (the driver 82a shown in Figs. 3 and 9 being representative) acting on a pick-up member 83. In known manner, the ribbon-feeding mechanism comprises levers 72, 73, Fig. 8, pivoted at 74, 75 beneath the top plate 23 and arranged to be rocked to rack the ribbon spools. These levers have forks 76 engaged by a pin 77 on a bar 86 the pivot end of which is hinged at 87 to a lever 84 carrying member 83, lever 84 being pivoted at 85 to the plate 23. Lever 84 also connects by pin 88 with lever 89 operating the usual ribbon guide 90.

Drivers 82a, 82b are rocked in known manner when a key of the associated keyboard 5a, 5b is struck. Considering the operation of 82a as an example, when a key 12a is struck, the latter pivots about pivot 78a, Fig. 3, and a heel 79a on it rocks frame 80a about pivot 81a; driver 82a is an upstanding finger on that frame.

The aforesaid ribbon guide 90 may also be shifted by the colour change lever 94a or 94b. Pin 88 is carried by link 95 on crank 96 the shaft 97 of which has a second crank 98 with a crank pin 99 arranged to be shifted by either colour change lever. All these parts of the ribbon feeding mechanism are themselves well known.

Reverting to a description of the carriage unit, the carriage 40 may incorporate a line space lever 54, a rack release lever 55, a carriage rack 56, and feed rollers 57, for feeding paper round the platen 39, all arranged in known manner.

The difficulty may arise that when the carriage unit 22 is being moved from one keyboard

unit to another, and particularly when it reaches the end of its movement, the momentum of the platen 39 may cause the latter to travel endwise on its runway. In order to prevent this the carriage unit incorporates mechanism, automatically brought into operation when the top plate 23 and the carriage unit 22 are raised, for locking the platen 39 in position. This mechanism is shown in Fig. 4 and consists of a catch 58 pivoted at 59 on the top plate 23 and caused by spring 60 to engage with the serrations on the tabulating bar or with the serrations of tabulating stops 62 thereon, and a plunger 63 which is slidably arranged on the top plate 23 and extends downwards to be engaged by a suitable abutment 64a or 64b on the frame 2a or 2b of the appropriate keyboard unit when the top plate is lowered into position. The plunger 63 is pressed downwards by a return spring 66 and the catch 58 automatically engages to lock the platen against endwise movement.

We claim:

1. A typewriting machine comprising a plurality of keyboard-units each having keys, an escapement-operating element, type bars and type-bar mechanism connecting said keys to said escapement-operating element and said type bars; a continuous guideway extending across all the keyboard-units, a carriage slideable along said guideway, latching means for holding said carriage stationary on said guideway opposite any of said keyboard-units, an escapement mechanism on said carriage, a platen carrier slideable along said carriage under control of said escapement mechanism and having a rotatable platen thereon, and a control connection on said carriage associating said escapement mechanism with the escapement-operating element of the particular keyboard-unit opposite which the said carriage is held stationary.

2. A typewriting machine comprising a plurality of keyboard-units each having keys, an escapement-operating element, a driver for a ribbon take-up mechanism, type bars and type-bar mechanism connecting said keys to said escapement-operating element, driver and type bars; a continuous guideway extending across all the keyboard-units, a carriage slideable along said guideway, latching means for holding said carriage stationary on the guideway opposite any one of said keyboard-units, an escapement mechanism on said carriage, a ribbon take-up mechanism on said carriage, a platen carrier slideable along said carriage under control of said escapement mechanism and having a rotatable platen thereon, a control connection on said carriage, associating said escapement mechanism with the escapement-operating member of the particular keyboard-unit opposite which the said carriage is held stationary, and a pick-up member on the said ribbon take-up mechanism associating such mechanism with the ribbon take-up driver of the same keyboard unit.

3. A typewriting machine according to claim 2 having a serrated tabulating bar on said platen carrier, a catch member on the said carriage with spring means urging it into engagement with the tabulating bar, a catch-release member on the carriage and an abutment on each keyboard unit lying in the path of said catch-release member to disengage the catch member from the said bar when the carriage is held stationary by said latching means at its selected positions on the guideway.

4. A typewriting machine comprising a plu-

plurality of side-by-side keyboard-units each having keys; an escapement-operating element, type bars and type-bar mechanism connecting said keys to said escapement-operating element and said type bars; a continuous guideway extending across all the keyboard-units, a carriage hingedly and slidably mounted on said guideway, a spring latch on each keyboard-unit, a latch engaging member on the carriage to engage the latch of the particular keyboard-unit opposite which the carriage is located when the carriage is pivotally lowered, a handle pivoted on the carriage the upward movement of which first releases the latch engaging member from said latch and then pivotally raises the carriage, an escapement mechanism on said carriage, a platen carrier slideable along said carriage under control of said escapement mechanism and having a rotatable platen thereon, a control connection on said carriage associating said escapement mechanism with the escapement-operating element of the said particular keyboard-unit, a serrated tabulating bar on said platen carrier, a pivoted spring latch on the carriage to engage serrations on the tabulating bar, a spring plunger mounted on the carriage with one end engaging the said latch, and an abutment member on each keyboard-unit in the path of the other end of said plunger as the carriage is pivotally lowered opposite said particular keyboard-unit.

5. A typewriting machine according to claim 4, having a guide channel on the carriage and having an upstanding arm between each two-by-side keyboard-units, said arm having a roller on its extremity to enter said channel when the carriage is pivotally raised and slid along the guideway.

6. A typewriting machine comprising a plurality of side-by-side keyboard-units, a guideway extending across all the units, a carriage movable on said guideway to operative positions opposite the respective keyboard-units, a platen carrier slideable on said carriage in the direction of the carriage movement, and means locking the platen carrier to the carriage when the carriage is moved from an operative position and releasing the said carrier from the carriage when the carriage is again brought to rest in an operative position.

7. A typewriting machine comprising a plurality of side-by-side keyboard-units each having keys, an escapement-operating element, a driver for a ribbon take-up mechanism, type bars and type-bar mechanism connecting said keys to said escapement-operating element, driver and type bars; a continuous guideway extending across all the keyboard units, a carriage hingedly and slidably mounted on said guideway, latching means for holding said carriage stationary on the guideway opposite any one of said keyboard-units, an escapement mechanism on said carriage, a ribbon take-up mechanism on said carriage, a platen carrier slideable along said carriage in the direction of the carriage movement under control of said escapement mechanism and having a ro-

tatable platen thereon; a control connection on said carriage associating said escapement mechanism with the escapement-operating member of the particular keyboard-unit opposite which the said carriage is held stationary, a pick-up member on the said ribbon take-up mechanism associating such mechanism with the ribbon take-up driver of the same keyboard-unit, a serrated tabulating bar on said platen carrier, a pivoted spring latch on the carriage to engage serrations on the tabulating bar, a spring plunger mounted on the carriage with one end engaging the said latch, and an abutment member on each keyboard-unit in the path of the other end of said plunger as the carriage is pivotally lowered opposite said particular keyboard-unit.

8. A typewriting machine comprising a plurality of side-by-side keyboard-units each having keys, an escapement-operating element, a driver for a ribbon take-up mechanism, type bars and type-bar mechanism connecting said keys to said escapement-operating element, driver and type bars; a continuous guideway extending across all the keyboard-units, a carriage hingedly and slidably mounted on said guideway, latching means for holding said carriage stationary on the guideway opposite any one of said keyboard-units, an escapement mechanism on said carriage, a ribbon take-up mechanism on said carriage, a platen carrier slideable along said carriage in the direction of the carriage movement under control of said escapement mechanism and having a rotatable platen thereon, a control connection on said carriage associating said escapement mechanism with escapement-operating member of the particular keyboard-unit opposite which the said carriage is held stationary, a pick-up member on the said ribbon take-up mechanism associating such mechanism with the ribbon take-up driver of the same keyboard-unit, a serrated tabulating bar on said platen carrier; a pivoted spring latch on the carriage to engage serrations on the tabulating bar, a spring plunger mounted on the carriage with one end engaging the said latch, and an abutment member on each keyboard-unit in the path of the other end of said plunger as the carriage is pivotally lowered opposite said particular keyboard-unit, said machine also having a guide channel on the carriage and having an upstanding arm between each two side-by-side keyboard-units, said arm having a roller on its extremity to enter said channel when the carriage is pivotally raised and slid along the guideway.

CLAUDE WELLINGTON BRUMHILL.
ARTHUR PATEMAN.
